(57) CLAIM

The ornamental design for an electronic stethoscope, as shown and described.

DESCRIPTION

FIG. 1 is a perspective view of an electronic stethoscope showing my new design;

FIG. 2 is a front view of the headset portion of the stethoscope, the rear view being a mirror image of the front view; FIG. 3 is a right side view thereof, the left side view being a mirror image of the right side;

FIG. 4 is a top view thereof;

FIG. 5 is a left side elevational view of the hand held portion of the stethoscope;

FIG. 6 is a front elevational view thereof;

FIG. 7 is a top plan view thereof;

FIG. 8 is a right side elevational view thereof;

FIG. 9 is a rear elevational view thereof; and,

FIG. 10 is a bottom plan view thereof.
